UNITED STATES PATENT OFFICE.

MORRIS P. WILLIAMS, OF GILBERTVILLE, MASSACHUSETTS.

SPINDLE-OILER.

1,360,845.

Specification of Letters Patent. Patented Nov. 30, 1920.

Application filed May 18, 1920. Serial No. 382,221.

To all whom it may concern:

Be it known that I, MORRIS P. WILLIAMS, a citizen of the United States, and a resident of Gilbertville, in the county of Worcester 5 and State of Massachusetts, have invented a new and Improved Spindle-Oiler, of which the following is a full, clear, and exact description.

This invention relates to improvements 10 in spindle oilers, an object of the invention being to provide improved means for oiling a series of spindles, such for example, as those employed on cap spinning and twisting frames, which results in rapidly and 15 uniformly applying the lubricant to the spindles without wastage of lubricant and without soiling the parts of the machine or the floor.

A further object is to provide mechanism 20 of the character stated which can be adjusted to suit the particular machine and can be moved longitudinally along the lifter rail of the machine and operate to lift the sleeve carrying spools on the spindles and 25 apply by means of a brush the proper quantity of lubricant to each spindle as the device moves along the rail.

A further object is to provide mechanism 30 of the character stated which not only directs the brush against the spindle, but also serves as a support and guiding means for the oil can to direct the oil onto the brush.

With these and other objects in view the invention consists in certain novel features 35 of construction, and combinations and arrangements of parts, as will be more fully hereinafter described and pointed out in the claims.

In the accompanying drawings—

40 Fig. 1 is a view in longitudinal section illustrating my improved device in operative position.

Fig. 2 is an end elevation of my improved device.

45 Fig. 3 is a view in transverse section on the line 3—3 of Fig. 1.

Fig. 4 is a view in longitudinal section on the line 4—4 of Fig. 2.

50 1 represents the lifter rail of an ordinary cap spinning or twisting frame through which spindles 2 project and on these spindles the spool carrying sleeves 3 are mounted. These spindles are ordinarily arranged in a relatively long series and it is

the purpose of my invention to provide improved means for lubricating the series of spindles by moving my improved device along the rail 1 as will hereinafter appear.

4 represents a tubular handle which constitutes the gripping and holding means of my improved oiler. This handle 4 is secured at its inner end to a plate 5 and said plate 5 is made with recessed and slotted guideways 6 in which are accommodated the heads 7 of internally and externally screw threaded adjusting sleeves 8 having enlarged finger holds 9 at their inner ends. Screws 10 are located in said sleeves 8 and support at their inner ends an angle rail 11, said angle rail 11 adapted to engage over the edge of the rail 1 of the spindle machine and support my improved device in operative position relative thereto and also permit longitudinal movement of the device along the rail 1.

75 Washers 13 are located on the sleeves 8 against the outer face of the plate 5 and wing nuts 14 are located on the sleeves 8 and are adapted to bind the washers 13 against the plate to secure the sleeves 8 in any position of adjustment of the rail 11. By turning the sleeve 8 after the wing nut 14 is loosened, the rail 11 can be moved toward or away from the plate 5 to give the desired position of the parts relative to the spindles, 80 as will more fully hereinafter appear.

85 Inside of the handle 4 I adjustably secure a guide member 15. This guide member 15 may constitute an ordinary casting having a lower bore 16 to accommodate the 90 tubular handle 17 of a brush 18, and said member 15 is also made with an upper longitudinal bore 19 to accommodate the spout 20 of an oil can 21, said spout and brush projecting through an opening 22 in the 95 plate 5 registering with the end of the handle 4.

100 The handle 4 is made with a longitudinal slot 23 receiving the headed end of a set screw 24, said set screw projected through the tubular handle 17 of the brush 18 and having a nut 25 inside of said handle 17 so that when said screw is clamped, it will operate to clamp the brush against movement and also hold the guide member 15 against 105 movement in the handle 4.

The plate 5, above referred to, is of general triangular form and is provided

throughout its upper edge with a cam flange 26, said flange having a tongue or extension 27 at one end adapted to engage under a sleeve 3 and cause the sleeve to ride over the 5 cam flange, thus elevating the sleeve and the spool carried thereby so that the spindle 2 can be lubricated.

By reference to Fig. 1, it will be noted 10 that the brush 18 is in position to engage the spindle 2, and the spout 20 discharges above the brush dropping the oil onto the brush and maintaining the latter supplied 15 with lubricant so that while the oil can accurately supplies the lubricant, the brush directly applies the same to the spindle. The tapering bore 19 of the guide member 15 limits the inward movement of the tapering spout 20 so that the inner end of said spout is accurately positioned relative to the 20 brush.

The operation is as follows: The rail 11 of my improved oiler is located against the 25 edge of the lifter rail 1 and the handle 4 is grasped with one hand while the oil can 21 is supported by the other hand of the operator. As the device is moved longitudinally 30 of the rail 1, the cam flange 26 will operate to lift the spools 3 to the position shown in Fig. 1, and while in this position the brush 35 18 will rub against the spindle and apply the proper amount of lubricant thereto. Hence, it is simply necessary to move the oiler along the rail of the machine and the spools will be lifted in turn and lubricant in proper proportions supplied to each spindle preventing wastage of lubricant and soiling of the machine or floor.

Various slight changes might be made in 40 the general form and arrangement of parts described without departing from the invention, and hence I do not limit myself to the precise details set forth, but consider myself at liberty to make such changes and alterations as fairly fall within the spirit 45 and scope of the appended claims.

I claim:

1. A device of the character stated, comprising a handle, a rail operatively connected to the handle, said handle adapted to support a lubricant applying brush and the 50 spout of an oil can above the brush, and a spindle moving cam flange on said handle above the rail.

2. A spindle oiler, comprising a handle, 55 spindle moving means on the handle, a plate on the handle, a rail operatively connected to the plate and adapted to guide the movement of the oiler, a brush carried by the oiler, and means in the handle for supporting an oil can spout above the brush.

3. A spindle oiler, comprising a handle, a 60 plate on the handle, a rail operatively connected to the plate and adapted to guide the movement of the oiler, a brush carried by the oiler, means in the handle for support-

ing an oil can spout above the brush, and a spindle moving cam flange on the upper portion of said plate.

4. A spindle oiler, comprising a handle, a 70 plate on the handle, a rail operatively connected to the plate and adapted to guide the movement of the oiler, a brush carried by the oiler, means in the handle for supporting an oil can spout above the brush, and means for adjusting the rail relative to the 75 plate.

5. A spindle oiler, comprising a handle, a 80 plate on the handle, a rail operatively connected to the plate and adapted to guide the movement of the oiler, a brush carried by the oiler, means in the handle for supporting an oil can spout above the brush, a cam flange on the upper portion of said plate, and means for adjusting the rail relative to the 85 plate.

6. A spindle oiler, comprising a handle, a 90 plate on the handle, a rail operatively connected to the plate and adapted to guide the movement of the oiler, a brush carried by the oiler, means in the handle for supporting an oil can spout above the brush, and means permitting longitudinal adjustment of the brush and the spout in the handle.

7. A spindle oiler, comprising a handle, a 95 plate on the handle, a rail operatively connected to the plate and adapted to guide the movement of the oiler, a brush carried by the oiler, means in the handle for supporting an oil can spout above the brush, a cam flange on the upper portion of said plate, 100 and means permitting longitudinal adjustment of the brush and the spout in the handle.

8. A device of the character stated, comprising a tubular handle, a guide member in 105 the handle having upper and lower longitudinal bores, a brush secured in the lower bore of said member, said upper bore of the member adapted to receive the spout of an oil can, a plate secured to the handle and having a cam flange thereon, a rail operatively connected to the plate and adapted to guide the movement thereof, and a spindle sleeve engaging the cam flange on the upper portion of said plate.

9. A device of the character stated, comprising a tubular handle, a guide member in the handle having upper and lower longitudinal bores, a brush secured in the lower bore of said member, said upper bore of the 120 member adapted to receive the spout of an oil can, a plate secured to the handle and having a cam flange thereon, a rail operatively connected to the plate and adapted to guide the movement thereof, a spindle sleeve 125 engaging the cam flange on the upper portion of said plate, said plate of general triangular form, and a tongue at one end of the cam flange adapted to engage under the spindle sleeve.

10. A device of the character stated, comprising a handle, a brush and oil can guided in the handle, an angular rail, a plate secured to the handle, screws secured to the rail and projecting through the plate, and means operatively engaging the screws permitting longitudinal and vertical adjustment of the screws and the rail.

11. A spindle oiler, comprising a support, a lubricating device on the support, means 10 on the support for guiding the movement thereof transversely of a series of spindles, and means on the support for imparting longitudinal movement to the spindles during said transverse movement of the support.

MORRIS P. WILLIAMS.
